UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

DESIGN FOR A LAMP DOOR.

Application filed May 12, 1923 Serial No. 6,149. Term of patent 14 years.

To all whom it may concern:

Be it known that I, CHARLES E. GODLEY, a citizen of the United States, residing at Detroit, in the county of Wayne and State of Michigan, have invented a new, original, and ornamental Design for Lamp Doors, particularly doors for the signal lamps of automobiles, of which the following is a specification, reference being had to the ac-

companying drawing, forming part thereof, of which—

Fig. 1 is a front elevation and Fig. 2 an end elevation of a lamp door embodying my new design.

I claim:—

The ornamental design for a lamp door, as shown.

CHARLES E. GODLEY.
